EXTENSION TABLE

John O. Van Koert, New York, N. Y., assignor to Drexel
Furniture Company, Drexel, N. C., a corporation of Delaware

Application August 2, 1955, Serial No. 37,266

Term of patent 7 years

(Cl. D33—14)

Fig. 1.

Fig. 2.

I claim:

The ornamental design for an extension table, as shown.
